BED MOUNTABLE SUPPORT FOR A PORTABLE TELEVISION SET

Peter L. Lindenmuth, Boston, Mass., assignor to Wells
Television, Inc., New York, N.Y., a corporation of
New York

Filed May 26, 1965, Ser. No. 85,472

Term of patent 14 years

(Cl. D33—3)

FIG. 1.

FIG. 2.

FIGURE 1 is a perspective view of a bed mountable support for a portable television set showing my new design; and

The broken lines shown in FIGURE 1 are for illustrative purposes only.

I claim:

The ornamental design for a bed mountable support for a portable television set, substantially as shown and described.
